ATTORNEY

UNITED STATES PATENT OFFICE.

NICHOLAS LEIST, OF NEW ALBANY, INDIANA.

DESIGN FOR A BADGE.

SPECIFICATION forming part of Design No. 27,374, dated July 20, 1897.

Application filed April 17, 1897. Serial No. 632,674. Term of patent 14 years.

To all whom it may concern:

Be it known that I, NICHOLAS LEIST, a citizen of the United States, residing at New Albany, in the county of Floyd and State of Indiana, have invented and produced a new and original Design for a Badge, of which the following is a full, clear, and exact description, reference being had to the accompanying drawing, forming part thereof.

- 10 My design is illustrated in the drawing, which represents a badge, its main portion representing in outline and surface ornamentation a haystack *a*, mounted upon an ornamental name-plate *b*, formed by a segmental 15 panel. Extending from different points of the haystack, as if arranged against the back thereof, are the respective handles *c*' and *d*' of a hay-fork *c* and a rake *d*, said handles being angularly arranged in relation to each 20 other and also extending beyond the ends of the name-plate *b*, substantially as shown. Upon the face of the haystack is the representation of the handle *e*' of a scythe, said handle extending from one side of the haystack, 25 near the top thereof, and terminating in the representation of a scythe-blade *e*, arranged horizontally above the top of the hay-

stack. The handle *e*' connects with one end of the rake *d*, while the pointed end of the scythe-blade *e* is formed integral with the 30 tines of the fork *c*. Perched upon the upper edge of the scythe-blade *e* is an eagle having its wings spread and the representation of a shield upon its breast.

The essential feature of my novel design 35 consists in the arrangement of the main body, made to represent a haystack, ornamented by the crossed arrangement of farmers' implements, as the hay-fork, rake, and scythe, and the blade of the scythe being ornamented 40 with an eagle bearing a shield, substantially as described.

Having thus described my invention, what I claim is—

The design for a badge, substantially as 45 herein shown and described.

In testimony that I claim the invention set forth above I have hereunto set my hand this 6th day of April, 1897.

NICHOLAS LEIST.
